HANDLE FOR BURIAL RECEPTACLES

Victor R. Preston, Galesburg, Ill.

Application April 15, 1935, Serial No. 16,380

6 Claims. (Cl. 16—115)

This invention is directed to handles for burial receptacles and has for its principal object to provide a handle mechanism attachable to burial receptacles or other containers, which is capable of movement in a horizontal plane in such a manner that the handle may be positioned away from the receptacle so as to be convenient for use, or moved into position adjacent the surface of the receptacle so that the receptacle as a whole will occupy less space.

Another object is to provide a mechanism as aforesaid having means whereby the handle may be locked in several positions of use.

An additional object is to provide a burial receptacle having handles movable toward or away from the sides thereof by means of a horizontal movement.

A further object is to provide a handle mechanism as aforesaid, which will have a neat appearance.

It is well known that, in practical use of burial receptacles and the like, the handle portion forms a very necessary portion of the equipage, and the conditions of use require that such receptacles must be provided with handles which are not only rugged and of pleasing appearance but in addition must be so designed that they may be positioned away from the surface of the receptacle so as to be easily grasped by the hand or re-positioned adjacent such surface so that the receptacle may be placed in a close fitting outer receptacle. It is obviously desirable that the handle be lockable in its several positions so as to avoid movement of the handle at unexpected or undesirable times.

To accomplish the object set forth I provide a mechanism disclosed in the following description and accompanying drawings, in which;

Figs. 1 and 2 are side elevational views showing a receptacle to which my invention is applied for practical use.

Fig. 3 is a fragmental sectional plan view taken on line 3—3 in Fig. 2.

Fig. 4 is a sectional elevational view showing details of mechanism to be described, taken on line 4—4 in Fig. 3.

Fig. 5 is a view similar to Fig. 4 showing details of a modification of construction which will be referred to.

Fig. 6 is an enlarged fragmental sectional elevational view showing details of construction to be described, taken from line 6—6 in Fig. 4.

Fig. 7 is an enlarged sectional view taken on line 7—7 in Fig. 5, and

Fig. 8 is a fragmental sectional plan view taken from line 8—8 in Fig. 6.

Referring to the drawings, Figs. 1, 2, and 3 disclose my invention as comprising handle bars 10 or 11 which are secured to a burial receptacle 12 or the like, the arrangement of bars 10 and 11 shown in Figs. 1 and 2 being optional. As will later appear, any desired combination may be used.

The handle bars are supported upon the receptacle by means of a support fixture mechanism which is shown in detail in Figs. 4 to 8.

In Fig. 4 the mechanism is shown as comprising a back plate 13 having an off-set portion 14 adapted to receive a bracket member 15 and to be attached thereto in a pivotally movable manner by means of a pin 16.

The bracket 15 includes an enlarged end portion 17 which is provided with an open area 18. The lower surface of portion 17 is fashioned to have downwardly directed dentures 19 which are adapted to engage complementary dentures 20 formed in the upper surface of a band or collar member 21 which latter is fashioned to receive and support the handle bar members 10—11 as shown.

Fig. 6 discloses a shank member 22 which is secured in the wall of the handle bar and in the body of member 21 whence it extends through the lower part of portion 17, being fitted therein in a movable manner, to a point somewhat above portion 17 whereat it is fitted with a knob member 23.

The knob 23 has an ornamental design and has a downwardly directed skirt portion 24 which is so dimensioned as to enter the area 18 as shown.

A coil spring 25 reacts between the bottom of portion 17 and the under side of knob 23 to urge the handle structure upwardly to normally hold dentures 19 and 20 in locking engagement which engagement may obviously be broken by means of depressing the knob 23 or the handle bars so as to compress spring 25 to move dentures 19 and 20 out of engagement. With the parts in the latter position it will be quite obvious that the brackets 15 may be rotated upon their pivots to permit movement of the handle bars toward the surface of the receptacle as shown in dotted lines and indicated by arrows in Fig. 3, whereupon release of the downward pressure on the handle bars will permit spring 25 to re-engage dentures 19 and 20 to lock the bars in a closed position as indicated in dotted lines.

The dentures 19 and 20 are so arranged as to

be engageable to lock the mechanism when the handle bars are in either open or folded position. Thus it will be apparent that with the bars in closed position a slight pressure downward on them will unlock the mechanism, whereupon the bars may be moved to usable position, the downward pressure relieved and a locked relation automatically established.

In Figs. 5 and 7 I show a modification of the structure wherein the locking devices are disposed at the pivot instead of the outer portion of bracket member 15.

In the latter arrangement the portion 17' is equivalent to portion 17 of Fig. 4, but does not include dentures 19 and 20, there being a single pivotal connection between portions 21' and 17'. Plate 13' is equivalent to plate 13 of the formerly described structure and the upper branch of bracket 15 has a portion 26 which movably fits in a receptacle formed in structure 13' and a coil spring 27, retained by a pivot pin 28, urges the structure upwardly. The lower part of the back plate structure 13' is provided with dentures 29 while the upper surface of the lower branch of bracket 15 is provided with complementary dentures, the whole being held in engagement by means of spring 27. Dotted lines indicate that the bracket 15 may be forced downwardly as by pressure upon the handle bars to disengage dentures 29 to thereby permit pivotal movement and subsequent locking of the mechanism as already described.

It is to be noted that the device above described is capable of wide variations in structure and design without alteration of the principle disclosed.

It is obviously possible to provide an elongated handle bar such as 11 in Fig. 2, having a bracket mechanism disposed at each end thereof whereby the center fixture shown is eliminated. It will be apparent that only one, of any number of support fixtures used on a single bar, may be provided with the locking mechanism described, while the associated fixtures attached to the same bar may not include the locking device. Obviously this arrangement would provide a structure having all the advantages described and the cost of the fitting as a whole reduced.

In the arrangement shown in Fig. 1 only one fixture of each of the handle bars 10, need be provided with locking devices, the associate fixtures being controlled and arranged to operate in unison with the locking fixtures by reason of their being attached to a unitary bar.

What I claim is:

1. A handle device for burial receptacles comprising an arm pivotally supported thereon for pivotal movement to different positions with re-

spect to the receptacle in a plane parallel to the bottom of the receptacle, means for latching the arm in one of its positions and a handle member attached to the arm in a manner to be moved therewith to different positions with respect to the receptacle. 5

2. A handle device for burial receptacles comprising an arm supported thereon for pivotal movement in a horizontal plane to different positions with respect to the receptacle, a handle member pivotally attached to the arm, the same being movable therewith into several positions with respect to the receptacle and pivotally movable upon the arm and means for latching the handle member against such movement. 10 15

3. A handle for a burial receptacle comprising an arm supported thereon for pivotal movement in a horizontal plane, a handle member pivotally supported on the free end of the arm lying substantially parallel to the wall of the receptacle, 20 said handle being movable toward or away from the receptacle by means of pivotal movement of the arm without alteration of its parallel relation.

4. A handle mechanism for burial receptacles including in combination a fixture secured to a 25 wall of the receptacle, an arm pivotally mounted on said fixture with the axis of the pivot lying perpendicular to the bottom of the receptacle, a horizontal bar handle mounted on the arm, the arm being movable longitudinally of the pivot and rockable thereon and means operable by said longitudinal movement for latching the arm against rocking movement. 30

5. A handle mechanism for burial receptacles including in combination a fixture secured to a 35 wall of the receptacle, an arm pivotally mounted on said fixture with the axis of the pivot disposed perpendicular to the bottom of the receptacle, a horizontal bar handle member pivotally mounted on said arm in a manner to be 40 moved pivotally with respect to the arm and longitudinally of the axis of said pivot and means operable by said longitudinal movement to latch the handle against pivoted movement thereof on the arm. 45

6. A handle mechanism for burial receptacles including in combination a fixture secured to a wall of the receptacle, a horizontal bar handle having one end pivotally mounted on said fixture in such a manner that the free end may be moved toward or away from the receptacle by means of pivotal movement in a plane parallel to the bottom of the receptacle and co-operative means on the handle and fixture for latching the handle against said pivotal movement. 50 55
